UNITED STATES PATENT OFFICE.

MAX H. BURGER, OF BRADLEY BEACH, NEW JERSEY.

DESIGN FOR A CANDLE-LAMP.

47,483.

Specification for Design.

Patented June 22, 1915.

Application filed February 12, 1915. Serial No. 7,681. Term of patent 7 years.

To all whom it may concern:

Be it known that I, MAX H. BURGER, a citizen of the United States, residing at 417 Main street, in the city of Bradley Beach, county of Monmouth and State of New Jersey, have invented a new, original, and ornamental Design for a Candle-Lamp, of which the following is a specification, reference being had to the accompanying drawings, forming a part thereof, and in which—

Figure 1 is a side elevation. Fig. 2 is a top view. Fig. 3 is a view in elevation with a portion broken away to show the candle.

I claim—

The ornamental design for a candle lamp, as shown.

MAX H. BURGER.
